BURTON McCOLLUM, OF WASHINGTON, DISTRICT OF COLUMBIA.

SQUIRREL-CAGE ROTOR.

1,044,217.

Specification of Letters Patent. Patented Nov. 12, 1912.

Application filed December 6, 1911. Serial No. 664,219.

To all whom it may concern:

Be it known that I, BURTON McCOLLUM, a citizen of the United States, and a resident of Washington, District of Columbia, 5 have invented a new and useful Improvement in Squirrel-Cage Rotors, of which the following is a specification.

My invention relates to the type of alternating current induction motor having a 0 rotor known as the squirrel cage rotor, and has for its object the improvement of the operating characteristics of such motors. In practice such motors possess certain disadvantages in that they have a nearly 5 constant resistance in the secondary circuit, for which reason, as is well known, it is impossible to secure in one motor both high starting torque and high running efficiency, together with close speed regulation. Further, such motors as ordinarily constructed 0 have an inherently low power factor, which also is objectionable in practice. With a view of overcoming the first of these difficulties, it has heretofore been proposed to 5 use as short circuiting rings of the rotor thin sheets of metal having a positive temperature coefficient of resistance, and adapted to be heated to a high temperature by the starting currents of the motor. While it is 0 true that this device has a tendency to produce a higher resistance at starting than under running conditions, it has not been possible with the construction heretofore used to obtain anything like the variation of 5 resistance desired. This is due chiefly to the fact that the short circuiting rings which form a part of the rotor circuit are of necessity of considerable length, and unless they are made of large cross section they 0 will introduce a high resistance into the rotor circuit even under running conditions, and this causes the motor to operate at a low efficiency and with poor speed regulation. If, on the other hand, the short circuiting 5 rings are made of sufficiently large cross section to give the desired low resistance they will contain so much metal and their capacity for absorbing heat will be so great that they will heat up very slowly when the 0 current is turned on, thus causing the motor to start very slowly under heavy loads or to fail to start altogether. Further, for the reason mentioned above, it is impossible with this construction to use anything but a 5 metal having a high conductivity such as copper, for these end rings, so that the

amount of metal may be kept small, but since copper and all other known materials having a high conductivity, have also a relatively low temperature coefficient of resistance, it will readily be seen that the results obtained by this construction cannot be adequate. In a previous application, Serial No. 612,118, filed Mar. 3, 1911, I have described one means of avoiding this difficulty, which means consists essentially in inserting permanently in the short circuiting devices of the rotor circuits, resistance elements of the type described below. I have now discovered other and simpler means by 60 which the above mentioned difficulties may be avoided, and I am thereby enabled not only to produce a motor having at once a high starting torque and high efficiency, but owing to the peculiar properties of the resistance devices used by me the power factor 65 of the motor under normal running conditions is greatly improved, and the maximum torque which the motor is capable of exerting is materially increased. Further, 70 owing to the greater mechanical simplicity of the resulting structure, the cost of the rotor is materially reduced. A full and complete description of my invention is contained in the annexed specification, reference being 75 made to the accompanying drawings.

My invention consists essentially in inserting in each of the conductor bars of the squirrel cage winding a resistance element having a relatively small cross section and 80 a positive temperature coefficient of resistance, preferably one characterized by an abrupt rise of resistance at a critical value of current due to the heating effect of the current in said resistance element.

Of the drawings: Figure 1 is a side elevation partly in section of the rotor of the motor to which my invention applies, showing an arrangement of the resistors in the squirrel cage winding that I have found 95 satisfactory. Fig. 2 is an end elevation showing the same structure and having a portion of the short circuiting ring broken away. Fig. 3 is a perspective view of one of the conductor bars of the squirrel cage. Fig. 4 shows a particular form of resistance element. Fig. 5 shows another form of resistance element and a method of connecting the same to the conductors of the squirrel cage.

In thus inserting the resistance elements in series with the conductor bars of the

squirrel cage, two important advantages are obtained. It is not then necessary to use a fixed length of resistance element as is the case when the resistance element constitutes the short circuiting ring of the rotor winding, but it is permissible to use a resistance element as short as desired. For this reason I am able to make the resistance elements of very small cross section and, at the same time, to make them of such short length that the resistance under normal running conditions will not be high enough to affect seriously the efficiency and speed regulation of the motor. In this way I am enabled to use metals having a much higher specific resistance than has heretofore been practicable, and can therefore use those metals which give the greatest increase of resistance with rise of temperature, and at the same time the quantity of metal in the resistors can be kept so small that it heats very rapidly when the current is turned on, thus producing a very rapid rise in resistance and a correspondingly rapid increase in the torque. Further, by thus inserting the resistance elements in the conductor bars of the rotor, the current carried by each element will be relatively small compared to the current in the short circuiting rings, and the resistance elements can therefore more readily be made of small cross section and a more rapid rise in resistance is secured. Also, in this case a single short circuiting ring only is required on each end of the rotor and a better mechanical construction is obtained.

I have experimented with many substances as resistance elements and have found that the magnetic metals, iron, nickel and cobalt are much better than any others, in that they show a very great and abrupt rise of resistance at a certain well defined critical value of current. It is characteristic of these metals that when used in a comparatively pure state they show a relatively low and only slightly changing resistance as the current is increased up to a certain critical value, at which point any further increase in current causes the resistance to rise very quickly to a manifold value. My invention consists further in so proportioning the resistance element that the normal load currents in the rotor will be somewhat below the critical value necessary to cause the abrupt rise of resistance, but so that the starting currents of the rotor will exceed this critical value. By this means, I am enabled to secure a resistance at starting equal to many times the resistance under running conditions, and thus obtain a high starting torque without sacrificing good efficiency and speed regulation. Further, by thus making the resistance elements of very short length and correspondingly small cross section, two other

important improvements in the operating characteristics are obtained. Under normal operating conditions the frequency of the alternating currents in the secondary circuit of an induction motor is very low. Since the temperature, and therefore the resistance of the resistance elements, tends to vary with the current strength, it is evident that the resistance of these elements will pulsate more or less when carrying alternating currents of low frequency. If, however, the resistance elements contain large amounts of metal, their capacity for absorbing heat will be so great that the pulsations in resistance will be imperceptible. However, by inserting the resistance elements in the rotor bars, in which case they can be made of very small dimensions as described, their capacity for absorbing heat is so small that relatively great pulsations in resistance will occur with the low frequencies that usually prevail in the secondaries of induction motors in practice. Herefrom follows the important advantages referred to above.

Since the heat in the resistance element is increasing and the resistance therefore rising as long as the square of the current in the element is above its mean value, approximately speaking, it follows that the resistance of the element will continue to increase for some time after the current has passed through its maximum value, and, as a result of this, the maximum of current is made to occur sooner than it would if the resistance were unvarying. The effective current in the rotor is therefore advanced in phase, a condition that improves the power factor of the motor and enables it to exert a higher maximum torque as mentioned above. This pulsation in resistance is greatly augmented by using materials having a relatively great tendency to increase their resistance with increasing current, such as the magnetic materials, and these metals are therefore best suited to securing all of the advantages mentioned above, viz: high starting torque combined with high efficiency, good speed regulation, improved power factor and high maximum torque.

If iron or cobalt be not worked at too high a temperature they are quite stable in air, and will, under such circumstances, have an indefinite life. When, however, it is desired to operate them at very high temperatures during the starting period in order to obtain the maximum increase in resistance, they may gradually oxidize and deteriorate. Nickel is much more resistant to oxidation than iron or cobalt, and at moderately high temperatures either nickel alone, or iron or cobalt coated with nickel makes a more satisfactory resistance element. When it is desired to push the tem-

peratures at starting to still higher values, beyond the point at which nickel oxidizes rapidly, it becomes necessary to coat the resistance element with some substance which does not oxidize readily at the temperature desired. This can readily be accomplished by numerous well known methods. Coatings of gold or platinum are practicable examples of this embodiment of my invention.

Referring particularly to Figs. 1 and 2, 1 designates the laminated core of the rotor, 2 the conductor bars of the squirrel cage winding embedded in the slots of the rotor core, and 3 the short circuiting end rings of the squirrel cage. It will be observed that in the case illustrated there are inserted on each end of the rotor in alternate conductor bars, resistance elements 4, of very short length and greatly reduced cross section, these being proportioned in accordance with the principles set forth above. It should be understood that this alternate placing of the resistance elements on either end of the rotor is not essential to the satisfactory operation of the motor from an electrical standpoint. In so far as the electrical operation is concerned, the resistance elements might all be placed on one end of the rotor, or they might be grouped in any of a variety of ways that readily suggest themselves. It is desirable, however, that the heavy short circuiting rings 3, be each connected directly to some of the conductor bars in order to secure ample mechanical strength and rigidity. If the rings 3, be otherwise suitably braced and held in position, any other grouping of the resistance elements in the conductor bars will be satisfactory.

In the construction illustrated in Figs. 1 and 2, it will be seen that the resistance elements are not integral with the conductor bars, but consist of separate pieces of metal fastened on one end to the conductor bars, and on the other, to the end rings by soldering or other suitable means. In this case the resistance element may be of the same or different material from that of the conductor bar.

In Fig. 4 is shown a modified construction of the resistance element in which a short portion, 4', near the end of the conductor bar 2', is greatly reduced in cross section, the bar being connected to the end ring 3, by means of the screw 5.

In Fig. 5 is shown a still further modification of the resistance element. Here, the resistance element 4'' is not integral with the conductor bar 2'', and may be of the same or different material, and is connected therewith at one end by means of the screw 6. The other end of the resistance element 4'' is connected to the lug 7 by means of the screw 8, and this lug is in turn connected

to the short circuiting ring 3 by means of the screws 9. It will be understood that any combination of the essential elements of the construction shown may be used with equal satisfaction, the resistance elements being connected at either or both ends by means of solder, screws, rivets, bolts or clamps, or by any other suitable means designed to give a good and permanent electrical and mechanical connection.

In the annexed claims, I cover broadly the use of resistance elements of reduced cross section and positive temperature coefficient of resistance inserted in the conductor bars of the squirrel cage, and claim specifically the use of iron as the essential element in such resistors. That portion of the above disclosure which relates to the use of cobalt and nickel as the essential elements in the resistors is made the basis of two separate applications, Serial Nos. 684,419 and 684,420, filed Mar. 18, 1912, both entitled "Improvement in induction motors."

I claim:

1. In an induction motor having a squirrel cage winding, a series resistance in each of the bars of the winding, said resistances comprising portions of reduced cross section having a positive temperature coefficient of resistance, and characterized by an abrupt rise of resistance at a critical value of current.

2. In an induction motor having a squirrel cage winding, a series resistance in each of the bars of the winding, said resistances comprising portions of reduced cross section having a positive temperature coefficient of resistance, and characterized by an abrupt rise of resistance at a critical current value, and so proportioned that the normal starting currents in the rotor bars will be above the critical current value, and the normal load currents below the critical current value.

3. In an induction motor having a squirrel cage winding, a series resistance in each of the bars of the winding, said resistances comprising portions of reduced cross section composed of a magnetic material, and adapted to be heated to a relatively high temperature by the starting currents in the rotor bars.

4. In an induction motor having a squirrel cage winding, a series resistance in each of the bars of the winding, said resistances comprising portions of reduced cross section composed of iron, and adapted to be heated to a relatively high temperature by the starting currents in the rotor bars.

5. In an induction motor having a squirrel cage winding, a series resistance in each of the bars of the winding, said resistances comprising portions of reduced cross section having a positive temperature coefficient of resistance and coated with a material sub-

stantially non-oxidizable at the temperatures normally reached by the resistances.

6. In an induction motor having a squirrel cage winding, a series resistance in each of the bars of the winding, said resistances comprising portions of reduced cross section, composed of magnetic material coated with a material substantially non-oxidizable at the temperatures normally reached by the resistances.

7. In an induction motor, and in combination, a squirrel cage winding, a series resistance in each of the bars of said wind-

ing, said resistances comprising portions of reduced cross section, composed of a magnetic material coated with nickel.

8. In an induction motor, and in combination, a squirrel cage winding, a series resistance in each of the bars of said winding, said resistances comprising portions of reduced cross section, composed of a conductor of iron coated with nickel.
